UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

BUTTONHOLE-SEWING MACHINE.

Original application filed July 5, 1923, Serial No. 649,440. Divided and this application filed January 9, 1925. Serial No. 1,349.

This invention relates to automatic buttonhole sewing machines and has for an object to provide a high-speed machine particularly adapted for cloth work, whereby 5 a maximum production of stitched buttonholes may be obtained with a minimum of effort on the part of the operator; the buttonholes being finished when removed from the machine and requiring no subsequent 10 hand trimming operations. Another object of the invention is to provide the machine with an under thread and cord trimmer which is independent of the buttonhole cutting mechanism and hence applicable to machines which cut the buttonhole either before 15 or after the sewing period. Another object of the invention is to provide simplified means for freeing the under thread mechanism or loop-taker from the last needle-loop 20 customarily retained thereby. Still further, the invention has for an object to provide means for controlling the position of the purl of the overlying stitches of a fly-bar buttonhole. Further objects of the invention will appear from the following description and claims.

The machine of my copending application Serial No. 523,056, filed December 17, 1921, while of general application, is intended 30 more particularly for that class of trade to which the quality of the finished buttonholes is more important than the quantity of buttonholes produced per machine. The speed of the machine of my said copending application is limited because of the fact that it embodies stitch-forming mechanism of the so-called "I. B. H." (improved buttonhole) type wherein an upper reciprocating and laterally jogging needle makes two complete reciprocations for each stitch-forming cycle. It is impracticable to operate stitch-forming mechanism of this type at speeds easily attained by stitch-forming mechanism of the "H & H" type represented in my Patent 45 No. 1,162,207, of November 30, 1915. In stitch-forming mechanism of the "H & H" type, a lower curved slit-stitch needle cooperates with an upper straight depth-stitch needle; the latter making but one complete 50 reciprocation per stitch-forming cycle.

The machine of my said Patent No. 1,162,-

207, is intended primarily for leather work, such as the sewing of a series of buttonholes in a shoe upper and, for this work, an under thread and cord trimmer is not required, 55 as the buttonholes are stronger if the cord bridges the spaces between the buttonholes and extends in one continuous length throughout the series. When sewing buttonholes in cloth, however, it is desirable that 60 the cord and sewing threads be trimmed close to the last stitch so that each individual buttonhole will have a finished appearance on both sides when removed from the machine and will not have to be retrimmed by 65 hand.

To the attainment of the ends in view I have reorganized the machine of my said copending application, building into it 70 stitch-forming mechanism of the upper straight needle and lower curved needle type. The under thread and cord-trimmer is arranged to be operated by a cam on the rapid feed-shaft of the machine and is independent of the buttonhole cutting mechanism. An upper thread trimmer is arranged to sever the needle-thread at the end of the sewing period and means are provided for 75 thereafter shifting the work-holder away from the stitch-forming mechanism to draw the last needle-loop clear of the loop-taker and also to draw off safe lengths of under thread and cord prior to the action of the under thread and cord-trimmer. The purl of the overlying stitches of a fly-bar buttonhole is controlled by automatic mechanism 80 operated by the rapid feed-shaft for increasing the tension on the under thread during the sewing of said overlying stitches, whereby the purl will be pulled over to the curved 85 needle punctures and give the finished buttonhole an even, flat and desirable appearance. The present invention further comprises the novel combinations of parts and details of construction hereinafter described 90 and particularly pointed out in the appended claims.

In the accompanying drawings, Fig. 1 is a right-side elevation of a buttonhole sewing machine embodying the invention; the 100 parts being in their respective positions occupied when the machine is at rest. Fig.

2 is a left-side elevation of the machine. Fig. 3 is a front elevation of the machine with the work-supporting plates in section. Fig. 4 is a horizontal section through the bracket-arm standard of the machine and with the work-clamp removed to show in plan certain mechanism within the machine bed. Fig. 5 is a fragmentary rear end elevation of the machine. Fig. 6 is a transverse section through the machine bed showing the rapid-feed shaft and certain details of the automatic clutch-mechanism for connecting it to its rapid driving shaft. Fig. 7 is a top plan view of the left-hand work-clamping lever and its fulcrum block. Fig. 8 is an inner side elevation of the same. Fig. 9 is a fragmentary front elevation showing in dotted and full lines the under thread and cord-cutter in retracted and operative positions, respectively. Fig. 10 is a fragmentary plan view of the lower work-supporting plates of the work-clamp. Fig. 11 is a sectional view through the upper thread-tension and its support. Fig. 12 is a fragmentary side elevation, partly in section, of the mechanism for increasing the tension of the under-thread tension device. Fig. 13 is a detail perspective view of the under-thread tension-modifying lever. Figs. 14 to 19 inclusive are views illustrating the relative positions of the parts adjacent the sewing point at different periods of a buttonhole-producing cycle. Fig. 20 is a plan view of the corded side of a finished buttonhole, as removed from the machine and Fig. 21 is a fragmentary elevation within the machine bed showing certain details of the clutch-controlling mechanism for the rapid-feed shaft.

40 As disclosed in my copending application Serial No. 649,440, filed July 5, 1923, of which this application is a division, the machine is constructed with a hollow frame comprising a hollow rectangular bed 1 from one end of which rises the standard 2 of the bracket-arm 3 terminating in the head 4. The stitch-forming mechanism is constructed substantially in accordance with the disclosure of my said Patent No. 1,162,207, and the Allen & Crosby Patent No. 1,275,999, of August 20, 1918, and includes the upper eye-pointed straight needle 5 carried by the needle-bar 6 journaled in the head 4 for the usual reciprocatory and axial turning movements. The needle 5 makes depth-stitches only and cooperates with a lower curved needle 7 and loop-taker 8 which latter seizes a depth-stitch loop from the needle 5 and presents it for entry by the curved needle 7, the latter carrying a loop of under thread through the loop of upper thread and over the edge of the buttonhole-slit, positioning said under thread loop at the upper side of the work for entry by the upper needle in its next descent. Thus, the

upper needle makes but one complete reciprocation for each stitch-forming cycle and the mechanism operates smoothly at speeds much higher than are practicable with stitch-forming mechanism of the "I. B. H." type represented in my Patent No. 15,324, reissued April 4, 1922, and in the Allen & Faulkner Patent No. 1,372,473, of March 22, 1921.

The needle-bar 6 is connected as usual to be operated by the upper or needle-bar operating shaft 9 geared at 10 to be driven from the vertical shaft 11 at double the speed of the latter. The shaft 11 is geared at 12 to be driven by and at the same speed as the main sewing shaft 13.

The curved needle 7 and loop-taker 8 are mounted on the rotary turret 14 and are connected in the usual manner, substantially as represented in said Allen & Crosby patent, to be operated by the looper-operating shaft 15 which is geared at 16 to be driven by the main sewing shaft 13 at double the speed of the latter. The needle-bar operating shaft 9 and the looper operating shaft 15 are thus driven at the same speed, which is double the speed of the main sewing shaft 13. During the sewing, the needle-bar 6 and turret 14 are turned by the usual connections with the feed-wheel 17 to lay the stitches radially around the eyelet-end of the buttonhole. After the sewing is completed the parts are reversely turned to initial position. The needles operate through the crescent-shaped aperture in the usual needle-throat or button 18 carried by the turret 14; the button 18 being apertured as usual to guide the stay-cord 8.

The work-holder is of the usual construction substantially represented in my said reissued patent. It is adapted to move both laterally and longitudinally of the bed 1 to space the stitches around the buttonhole and to move the work relatively to the stitch-forming mechanism intermediate sewing periods to carry the work from buttonhole cutting position to sewing position and, in the present instance, from sewing position to thread-cutting position and back to initial or buttonhole cutting position. The work-holder comprises the lower work-supporting plates 19, separable to spread the buttonhole and the upper clamping feet 20 which are carried by the usual clamp-levers 21 operated by the connected rock-shaft sections 22, one of which, Fig. 1, carries the clamp-closing finger-lever 23 and rearwardly extending lever-arm 24 adapted to be depressed automatically to close the clamp by the roll 25 at the front end of the clamp-closing lever 26 fulcrumed at 27 on the frame member 2 and actuated through the usual latch-pin connection 28 with the continuously running pulley 29, as described in my said reissued patent. The other of the connected rock-

shaft sections 22, Fig. 2, carries the lever-arm 30 which when pushed forwardly to the position shown in Fig. 2, effects the opening of the work-clamp and the release of the 5 work.

The work-holder is equipped with the usual clamp-spreading and unspredding toggle device 31, Fig. 4, and connections represented in my said reissued patent and including the levers 32 and 33, which when pushed forwardly or toward the left, Fig. 4, respectively, effect the spreading and unspredding of the clamp. The work-clamp sections are mounted as usual on the cross-slide plate 34 15 which, in turn, is mounted on the longitudinal slide-frame 35.

The work-clamp derives the longitudinal components of its motion through the usual connection with a longitudinal feed-cam-groove in the feed-wheel 17. The lateral component of motion of the work-clamp is derived through the lever connection 36 with the lateral feed-cam groove 37 in the readily accessible controlling wheel 38 25 mounted externally of the sewing machine frame, preferably at the side of the hollow bed 1, on the rapid feed-shaft 39 which carries the bevel-gear 40 meshing with a similar gear 41 on the feed-wheel 17. The present feeding mechanism is of substantially the same construction as that shown in my said reissued patent, except that the main feed-wheel of the present machine has no lateral feed-cam groove; the lateral feed cam-groove in the controlling wheel being used 30 instead, throughout the buttonhole producing cycle. The connected feed-wheels 17 and 38 are driven at a slow speed during the sewing by means of suitable connections, such as represented in my said reissued patent, with 35 the vertical shaft 11. Intermediate sewing operations the connected feed-wheels are driven at a higher speed by means of the rapid feed-shaft 39 which is connected 40 through an automatically controlled clutch-mechanism with the rapid-feed drive-shaft 42. The rapid-feed drive and automatic clutch control are of substantially the construction represented in my copending application 45 Serial No. 537,381, filed February 18, 1922, and comprise the clutch 43, Fig. 6, and the continuously reciprocating clutch-operating bars 44, 45, which are latched in 50 their idle positions, Figs. 6 and 21, by means of the latches 46, 47. It will be understood, particularly from the disclosures of my said copending application, Serial No. 537,381, and my said reissued patent, that the release of the latch 47 permits the bar 45 to operate the clutch 43 to connect the shaft 39 to the rapid-feed drive-shaft 42, thus throwing the rapid-feed mechanism into operation, and release of the latch 46 permits the bar 44 to operate the clutch to throw the rapid-feed mechanism out of operation. The throw-

out latch 46 for the rapid-feed mechanism is connected to the lever 48, Fig. 21, which is operated by the tripping points 49 on the inner face of the controlling wheel 38. The rapid-feed throw-in latch 47 is connected to 70 an arm 50 on the rock-shaft 51. The shaft 51 carries arms 52 and 53, Fig. 1, the former being depressed by a cam 54 on the usual clutch-disk 55 fast to the buttonhole cutter-shaft 56 and the latter being elevated, as described in said copending application, by the vertical motion of the stopping tooth 57 carried by the usual stop-motion lever 58 which controls the connection of the sewing shaft 13 with the constantly running pulley 59.

The buttonhole cutting mechanism is substantially the same as that disclosed in my said copending application Serial No. 537, 381 and includes the usual cutter-levers 60, 85 61, Fig. 4, which are pivotally mounted at 62 on the travelling fulcrum-block 63; the latter receiving its travelling movements from the link connection 64 with the cutter-advancing and retracting cam 65 on the cutter-shaft 56. The cutter-shaft also carries the usual cutter-lever closing cams 66, 67. The disk 55 on the cutter-shaft constitutes the driven member of the usual one-revolution clutch device, the operation of which is controlled by movement of the usual cutter-clutch controlling lever 68 mounted on the vertical fulcrum-pin 69. As explained in my said copending application Serial No. 537,381, clockwise movements of the lever 68, Fig. 4, effects the coupling of the cutter-shaft 56 to the continuously rotating pulley 29 for one revolution after which the cutter-shaft is automatically uncoupled from 95 said pulley and brought to rest.

The period of operation of the stitch-forming mechanism is controlled through the stop-motion lever 58 and its usual link connection 70, Fig. 2, with the lever 71 having the follower tooth 72 which bears upon the controlling wheel 38. When the tooth 72 is engaged by the cam incline 73, the stop-motion lever 58 is rocked clockwise, Fig. 2, to start the stitch-forming mechanism which continues in operation until the declivity 74 passes the tooth 72, whereupon the spring 75 restores the stop-motion lever to stopping position, Fig. 2, and thereby arrests the action of the stitch-forming mechanism.

The machine is preferably equipped with means above the work for cutting and nipping the upper thread at the end of the sewing period. The mechanism employed is preferably constructed and operated substantially in accordance with the disclosure of my Patent No. 1,369,371, of Feb. 22, 1921. The left-hand clamp-foot 20, Fig. 7, has pivotally mounted thereon the usual thread-cutting and -nipping blades 76, 77, which 125 130

cooperate, respectively, with the ledger-blade 78 and slightly resilient bar 79 to cut and nip the needle-thread. The blades 76, 77 are operated by means of the usual rod 80 to which the spring 81 is connected to pull it rearwardly or from full to dotted line position, Fig. 8, to carry the blades 76, 77, into cooperative relation with the ledger-blade 78 and bar 79 to sever and nip the needle-thread. The rod 80 carries a latch-pin 82 which is engaged by the notched front end of the spring-pressed latch-lever 83 to hold the rod 80 in the position shown in full lines in Figs. 7 and 8. When the latch 83 is tripped, the upper thread cutter and nipper operates under the influence of the spring 81 to cut and nip the needle-thread.

Mechanism such as disclosed in my said Patent No. 1,369,371 is preferably provided for pushing the rod 80 forwardly to effect the release of the needle-thread during the sewing of the initial stitches and in time for the beginning end of said thread to be drawn down substantially flush with the work by the action of the stitch-forming instrumentalities. This mechanism comprises the cam 84, Fig. 1, which rotates continuously during the sewing, and the cam-actuated lever 85, 86, fulcrumed at 87, together with the end-wise movable latch-pin 88 which is carried by the lever arm 85 and is ejected by the cam 84 after the lever 85, 86, has performed its function of setting the cutting and nipping blades 76, 77, in open position and thus releasing the beginning needle-thread end.

The latch 83 is tripped by a connection with the sewing mechanism stop-motion device at the end of the sewing period, before the work-holder is shifted away from sewing position, by means of the vertical bar 89 which is pivotally connected at its upper end at 90 to the tension release lever 91. The bar 89 is guided in its motion by being slotted at 91 and confined to slide vertically by the headed screw 92 which passes freely through the slot 91 and into the bracket-arm 3. The bar 89 terminates at its lower end in a foot 93 beneath which the angular extension 94 of the latch-lever 83 is positioned at the end of the sewing period, Figs. 7 and 8. The upper thread tension device 95 and its release lever 91 are of usual construction represented in my Patent No. 1,346,102, of July 13, 1920; the lever 91 being operated from the tooth 57 of the stop-motion device through the usual connections represented in my said reissued patent. Such connections include the link 96, lever 97, and three-armed latch-lever 98 mounted on the vertical link 99 connected at its upper end to the lever 91, all cooperating in the manner disclosed in my said reissued patent.

The cutter-shaft 56 has mounted thereon a cam 100 such as disclosed in my copending application Serial No. 558,644, filed

May 5, 1922, which actuates the T-shaped lever 101, after the buttonhole has been cut, and as the cutter-levers are being retracted, to push the arm 32 of the clamp-spreading toggle device 31 forwardly and thus spread the work-clamp. The controlling wheel 38 carries a tooth 102, Fig. 2, which engages the follower 103 carried at the lower end of the lever 104 to rock the latter about its fixed pivot 105 and, through the link 106, actuates the rock-lever 107 and the push-rod 108 which latter rigidly carries the depending arm 109. The push-rod 108 engages the arm 30 of the work-clamp and moves the latter to the position shown in Fig. 2 to open the work-clamp. At the same time the arm 109 engages the free end of the lever 33 and pushes it forwardly to unspread the work-clamp. The tooth 102 on the controlling wheel engages the follower 103 just before the machine comes to rest with the parts in the positions shown in Fig. 2.

When sewing a fly-bar buttonhole under the usual conditions obtaining in prior buttonhole sewing machines, it is found that there is a tendency for the purl of the overlying stitches of the fly-bar to stand intermediate the rows of needle-punctures, whereas along the sides of the buttonhole the purl is drawn over to the edge of the buttonhole-slit or to the path of the curved needle. This variation in the position of the purl gives an undesirable appearance to the finished buttonhole. I have discovered that by providing means for increasing the tension on the under thread while sewing the overlying fly-bar stitches, the purl of such stitches may be drawn over to the curved needle-path and the desirable uniformity in the stitching preserved throughout the buttonhole.

Such means may conveniently comprise the fork 111 which is adapted to press directly upon one of the disks of the under thread tension device 115 and is mounted on the rock-shaft 112 journaled in the bearing lugs 113 on the stationary supporting plate 114 for said under thread tension device. Secured to the rock-shaft 112 is the arm 116 to the rearward end of which is secured the plate 117 having at its upper end a hole 118 for attachment of one end of the auxiliary tension spring 119, the other end of which is anchored to the adjustable pin 120. The plate 117 is forked at its lower end to embrace the necked front end of the push-pin 121 the rearward end of which bears upon the cam-wheel 122 fixed to the rapid-feed shaft 39. The pin 121 is slidably mounted in the bushing 123 secured to the machine frame. The major portion of the periphery of the cam-wheel 122 is circular and holds the pin 121 pressed forwardly so that the spring 119 cannot press the fork 111 upon the tension-disks 115.

When sewing the overlying stitches of the fly-bar or the stitches between the points *a* and *b*, Fig. 20, the cut-away portion 124 of the cam 122 encounters the pin 121 and is of a depth such that the spring 119 is free to exert its predetermined pressure through the fork 111 upon the tension disks 115, in addition to the pressure of the usual tension spring 125. By thus automatically increasing the tension on the under thread a predetermined amount during the sewing of the overlying fly-bar stitches, I have found that the purl will be drawn over to the slit-stitch needle-punctures and the finished button-hole will appear as in Fig. 20.

The under thread and cord-cutter is in many respects similar to that disclosed in my said copending application Serial No. 523,056. The present mechanism is, however, simpler in construction and is actuated independently of the buttonhole cutting mechanism so as not to be limited in its application to machines which cut the buttonhole after sewing. The present under-thread and cord-cutter comprises the scissors device including the ledger-blade 126 and cutting blade 127 pivoted at 128 to the ledger-blade. The ledger-blade is secured to the carrier-lever 129 pivoted at 130 to the front wall of the turret casing 131. The cutting blade 127 has a tail which carries the follower stud 132 operating in the stationary cam-slot 133. The cam-slot 133 is concentric with the pivot 130 of the thread-cutter carrying lever 129 throughout the major portion of its length but is formed at its upper end with an offset 134 which operates to close the scissors device after the latter reaches cutting position. The carrier-lever 129 is connected by the link 134 to the front end of the lever 135 fulcrumed at 136 to the bracket 137 on the machine bed. The rear end of the lever 135 carries a follower roll 138 entering the cam-groove 139 in the cam 122 fixed to the rapid-feed shaft 39.

The scissors device is timed to operate after the work-holder has been shifted rearwardly from sewing position a sufficient distance to effect the pulling of the last needle-loop clear of the looper 8 and the pulling off of sufficient lengths of under thread and cord for the beginning of a new sewing operation. When the scissors device is projected to cutting position, the point of the ledger-blade grazes the under surface of the work close to the last stitch and enters between the work and the under thread and cord, in substantially the same manner described in my said copending application Serial No. 523,056. In the present instance, however, the needle-thread is cut above the work before the work-holder is shifted away from sewing position and the rearward motion of the work-holder from sewing to thread-cutting position, pulls down the end

of needle-thread and draws the last needle-loop clear of the under thread mechanism. Hence no needle-loop gripper such as shown in my said copending application Serial No. 523,056 is required to clear the under thread mechanism of the last needle-loop.

The present machine is preferably provided with a cord-nipper to arrest the feed of the cord during the sewing of the initial stitches, so that the initial stitches will be slid along the cord until the first stitch is even with the end of the cord, whereupon the nipper is opened to allow the cord to run from the supply. The cord-nipper may conveniently be made up in the form of a lever 140 pivoted at 141 to a lug 141' on the machine bed. The lever 140 is formed between its ends with a cam-follower projection 142 adapted to be engaged by the cam sections 143 adjustably secured in the circular groove 144 in the inner face of the controlling wheel 38 by screws 145 which pass through slots 146 in the controlling wheel 38. The lever 140 has slidably mounted transversely of its free end a pin 147, the outer end of which is backed up by the adjustable leaf spring 148 secured to the lever 140 by the holding screw 149 and adjusting screw 150. The free end of the pin 147 is adapted to yieldingly nip the cord against the anvil surface 151 at a gap in the cord-guiding tube 152. One of the cam sections 143 operates to close the cord-nipper when the initial stitches are being sewed and the other cam section 143 operates to close the nipper during the action of the under thread-cutter to insure against overfeeding of the cord and to hold the cord against deflection during the cutting operation.

Operation.

105

The construction and operation of various parts of the machine not hereinbefore referred to are not novel per se and are shown and described in my said prior patents and copending applications.

The operator presses upon the finger-release 153 which through the usual connections described in my said copending application Serial No. 537,381, effects the release of the slide-pin 28 and the coupling for one revolution only of the clamp-closing lever 26 with the cam-groove 154, Fig. 5, in the continuously running pulley 29. The clamp-closing lever on its return movement operates as usual through the bar 155 to trip the buttonhole cutter clutch-controlling lever 68 and effect the coupling of the cutter-shaft 56 for one revolution only with the continuously running pulley 29. The cutter-shaft effects, in the order named, the cutting of the button-hole in the position shown in Fig. 14, the spreading of the buttonhole and the tripping of the latch 47 to couple the rapid-feed shaft 39 to its driver 42 to effect the rapid shift of

110

115

120

125

130

the cut buttonhole from buttonhole cutting position, Fig. 14, to sewing position, Fig. 15.

Just before the stitch-forming mechanism is started the cord-nipper 147 is closed. As 5 the curved needle 7 makes its first up-stroke, Fig. 15, it pulls back the end 156 of the under thread from the position shown in Fig. 14 to that shown in Fig. 15. The straight needle 5 passes through the loop presented 10 by the curved needle and as it rises from its first descent the lever 85, 86, is operated to open and set the upper thread-nipping and cutting blades; releasing the needle-thread end in time for it to be drawn down flush 15 with the work.

As the initial stitches are formed the end 156 of under thread is drawn back flush with the under surface of the work as shown in Fig. 16. When the initial stitches 157, 20 Fig. 16, are even with the end of the cord, the cord-nipper 147 is opened and the sewing proceeds in the usual manner around the buttonhole; the under thread tension being automatically increased by the action of the cam-controlled spring-pressed lever 111 when 25 sewing the overlying stitches of the fly-bar to draw the purl over to the curved needle punctures.

When the sewing is completed the action 30 of the stop-motion device releases the needle-thread cutting and nipping blades 76, 77 which nip and sever the needle-thread, as shown in Fig. 17, while the work-clamp is still in sewing position.

35 The rapid-feed is also tripped into action through the lifting of the arm 53 by connection with the stopping tooth 57 and the work-clamp is rapidly shifted rearwardly from sewing position to thread-cutting position, Fig. 18. This motion of the work-clamp draws out from the needle-throat 18 safe lengths of under thread and cord for the beginning of the next sewing operation and also draws the last needle-loop 158, 40 Fig. 17, clear of the looper 8, as shown in Fig. 18. The cord is again nipped and the scissors device 126, 127, projected to operative position to sever the end of needle-thread, the under thread and the cord close 45 to the end of the buttonhole. As the scissors device 126, 127, is retracted the work-clamp is fed forwardly from thread-cutting to buttonhole cutting or initial position, 50 whereupon it is unspread and opened to release the work, Fig. 19, by the action of the cam 102 carried by the external controlling wheel 38. When the work is removed, 55 safe ends of cord and under thread remain sticking out of the needle-throat.

60 The invention is not to be understood as limited to the particular form and arrangement of parts shown and described, as many modifications thereof within the scope of the appended claims will be obvious to those 65 skilled in the art.

Having thus set forth the nature of the invention, what I claim herein is:—

1. A buttonhole sewing machine having, in combination, stitch-forming devices, a work-holder, a stay cord-guide, a cord-nipper, a cord-cutter, a readily accessible controlling wheel and cam means on said controlling wheel and connections for controlling the period of operation of the stitch-forming devices and for operating said cord-nipper to arrest the feed of the cord during the sewing of the initial stitches of a buttonhole. 75

2. A buttonhole sewing machine having, in combination, stitch-forming devices including an upper depth-stitch needle and an under curved slit-stitch needle cooperating to sew a purled overseam, a workholder, means for relatively moving the stitch-forming devices and work-holder to sew a fly-bar 80 buttonhole, an under thread tension device, and automatic means for increasing the tension of the under thread tension device while sewing the finishing stitches at the end of a fly-bar buttonhole, thereby causing the 85 purl to be drawn over to the edge of the fly-bar. 90

3. A buttonhole sewing machine having, in combination, stitch-forming devices including an upper depth-stitch needle and an under curved slit-stitch needle cooperating to sew a purled overseam, a cord-guide, a work-holder, means for relatively moving the stitch-forming devices and work-holder to sew a fly-bar buttonhole, an under thread 95 tension device, a spring and connections for increasing the tension on the under thread a predetermined amount during the sewing of the overlying fly-bar stitches, and automatic means for controlling the action of said 100 spring. 105

4. In a buttonhole sewing machine, stitch-forming devices including upper thread mechanism and under thread mechanism, a spring tension device for the under thread, a spring-pressed auxiliary element acting under its spring pressure to increase the tension of said tension device a predetermined amount, and a cam and connections for holding said spring-pressed element ineffective in opposition to its spring, said cam having a depression permitting said spring-pressed element to increase the tension of said tension device. 110 115

5. A buttonhole sewing machine having, in combination, a hollow frame, stitch-forming devices, a work-clamp, clamp-closing means, a readily accessible controlling wheel mounted externally of said hollow frame, and cam means on said controlling wheel and connections for controlling the period of action of the stitch-forming devices and for opening the work-clamp. 120 125

6. A buttonhole sewing machine having, in combination, a hollow frame, stitch-form- 130

ing devices, a work-clamp, clamp-spreading means, a readily accessible controlling wheel mounted externally of said hollow frame, and cam means on said controlling wheel and connections for controlling the period of action of the stitch-forming devices and for unspredding the work-clamp.

5 7. A buttonhole sewing machine having, in combination, a hollow frame, stitch-forming devices, a work-clamp, clamp-closing

and spreading means, a readily accessible controlling wheel mounted externally of said hollow frame, and cam means on said controlling wheel and connections for controlling the period of action of the stitch-forming devices and for opening and unspredding the work-clamp.

10 In testimony whereof, I have signed my name to this specification.

EDWARD B. ALLEN.
